UNITED STATES PATENT OFFICE.

FRED A. VEITH, OF ARLINGTON, MINNESOTA.

DESIGN FOR A POPCORN-BAG.

47,085.

Specification for Design.

Patented Mar. 9, 1915.

Application filed October 12, 1914. Serial No. 866,391. Term of patent 7 years.

To all whom it may concern:

Be it known that I, FRED A. VEITH, a citizen of the United States, residing at Arlington, in the county of Sibley and State of Minnesota, have invented a new, original, and ornamental Design for a Popcorn-Bag, of which the following is a specification, reference being had to the accompanying drawing, forming part thereof.

The figure is a perspective view of a pop corn bag, showing my new design.

My ornamental design for a pop corn bag embodies a main receptacle A, to one side of which an auxiliary tapering receptacle B is attached.

I claim:

The ornamental design for a pop corn bag, as shown.

FRED A. VEITH.
